DISPENSING MECHANISM FOR BULK MATERIAL

William J. Kilpatrick, Detroit, and Leo F. Butler,
Highland Park, Mich.

Application March 20, 1946, Serial No. 655,808

3 Claims. (Cl. 222—185)

1

This invention relates to dispensing mechanisms and particularly mechanisms for dispensing bulk material.

An object of the invention is to provide a sliding shutter controlling the downward discharge of bulk material from a container, to provide for the spring retraction of such shutter, and to mount the shutter on the container in a convenient, novel, and inexpensive manner.

Another object is to close the downwardly directed outlet of a container by a closure formed with a smaller outlet and held in place by an annular cap screw threaded on the container, and to mount on said closure a sliding shutter controlling said smaller outlet.

Another object is to dispose within a container for bulk material a rotative agitator for such material, to journal such agitator in an outlet formed centrally of a closure for a downwardly directed outlet of the container, to control the outlet of said closure by a sliding shutter and to provide an actuating connection from the shutter to the agitator.

Another object is to dispose a rotary agitator for bulk material within a container having a downwardly directed outlet, to mount said agitator on a funnel shaped support having a central opening for the discharge of material, to control said opening by a slide disposed beneath the container, and to adapt the slide to actuate the agitator.

Another object is to provide an improved cabinet for receiving a set of inverted kitchen canisters and mounting them in a side-by-side relation, and to elevate said cabinet to permit insertion of a receptacle therebeneath to receive a discharge from a selected canister.

These and various other objects are attained by the construction hereinafter described and illustrated in the accompanying drawings, wherein:

Fig. 1 is a front view of our improved canister cabinet.

Fig. 2 is an end elevational view thereof.

Fig. 3 is a horizontal sectional view of the cabinet as adapted to receive three canisters, one thereof being shown, the section being taken on the line 3—3 of Fig. 1.

Fig. 4 is a vertical cross sectional view of the same, taken on the line 4—4 of Fig. 1.

Fig. 5 is a vertical sectional view of a mechanism for dispensing material from said canister, the section being taken on the line 5—5 of Fig. 3.

Fig. 6 is a transverse sectional view of said dis-

2

pensing mechanism, taken on the line 6—6 of Fig. 3.

Fig. 7 is a bottom plan view of said dispensing mechanism.

Fig. 8 is a horizontal sectional view of the dispensing mechanism, taken on the line 8—8 of Fig. 6.

In these views, the reference character 1 designates a cabinet, preferably substantially rectangular and supported at a suitable elevation by legs 2 whereof a pair is disposed beneath each end of the cabinet. Each pair of end legs are integrally connected by a vertical web 3, and a rod 4, rigidly interconnecting the webs 3, reinforces the leg structures and forms a stop predeterminedly limiting insertion of a cup or other receptacle 5 beneath the cabinet. The front of the cabinet has the nature of a removable door 6 affording access to the cabinet and having a pair of downwardly projecting pegs 7 on its ends insertible in sockets 8 formed in the leg structures. For manipulating such door, it is equipped with a knob 9 in its central upper portion, and such knob attaches to the door a spring latch 10 adapted for snap engagement with a keeper 11 formed on the cabinet top. The cabinet receives a desired number of inverted canisters 12 for holding such bulk materials as flour, sugar, and coffee, downwardly directed outlets of the canisters being formed by circular necks 13. The annular shoulders 14 formed by the canisters at their junctures with said necks seat upon the cabinet bottom 15 marginally of circular openings 16 in such bottom through which the necks 13 project. The bottom 15 seats at its ends on shelves 17 formed by the leg structures, and is secured to said shelves by rivets 18 or the like. Rearwardly of the openings 16 said bottom has a portion 19 projecting upwardly and rearwardly, in spaced relation to the rear wall of the cabinet. This portion affords support to walls 20 of the canisters which incline upwardly from the canister necks and extend substantially to the rear wall of the cabinet. The canisters are preferably of glass or other transparent material, and the door 6 may be formed with vertical slots 21 for observation of the levels of material in the respective canisters.

Describing now a dispensing mechanism, one of which controls the flow from each canister, a disk type closure 22 is held upwardly against the neck 13 by an annular cap 23 engaging external screw threads on said neck. These threads are preferably of the standard type used on fruit jars and the annular cap may hence also be of a

standard type. Said closure is held from rotation relative to the canister by forming the closure margin with a notch 22a receiving a downwardly projecting lug 22b on the canister neck. Rotatably seated on the closure 22 is a sheet metal support 24 for an agitator 25 extending some distance upward into the canister. The illustrated agitator is formed by two transversely crossed arched wires, but other types of rotary agitators will serve the same purpose. The support 24 comprises a central annulus 24a journaled in a central opening in the closure 22, and forms a funnel extending to said annulus substantially from the periphery of the canister outlet. Thus said annulus forms an outlet materially smaller than the canister outlet, and the support 24 by reason of its funnel shape is adapted to guide discharging material to said annulus. Fitted on the annulus 24a beneath the closure 22 is a ring gear 26, held in place by upsetting the lower margin of the annulus. Thus said gear serves as a means for preventing upward escape of the annulus from the opening in which it is journaled. To assure a driving connection between the gear and annulus, a plurality of lugs 27, inwardly projecting from said gear, are engaged in notches of the annulus (see Fig. 8). The gear 26 meshes with a toothed rack 28 secured in any desired manner to a sheet metal shutter 29 normally closing the outlet formed by the annulus and having a forwardly projecting handle portion 30 whereby it may be slid to uncover such outlet. Said shutter seats on a guide plate 31 having a circular opening 31a registered with the annulus 24a and having its lateral margins 32 upturned and rigidly attached to the closure 22, the shutter being confined between said margins. A coiled spring 33 disposed beneath the guide plate normally retracts the shutter, said spring having its front and rear ends attached respectively to the shutter and guide plate, and the front anchorage 33a of the spring serving as a stop to limit shutter retraction. Withdrawal of the shutter is limited through engagement with the guide plate of the hooked rear end 34a of a wire 34 rigidly carried by the shutter. In order that the shutter handles may not interfere with proper insertion of the canisters and dispensing mechanisms in place, slots 35 are extended from the openings 16 to the front edge of the bottom, providing passageways for said handles.

It will readily appear that through withdrawal of any of the sliding shutters, a desired amount of material may be released from any of the several canisters, the agitator being at the same time turned through a partial revolution to loosen the material and assure a free flow thereof. By extending the lugs 27 some distance into the annulus 24a, as best appears in Fig. 8, said lugs exert an agitating effect proportionate to their length. Such an effect is desirable within the

annulus, since the bulk material to be dispensed is under a maximum pressure within the annulus and moreover is subject to its greatest flow restriction. Said lugs may have any length and form suited to their exercising a desired agitating function.

What we claim is:

1. In a dispensing mechanism for bulk material, a container for such material having a downwardly directed outlet formed within an annular neck of the container, such neck having a screw thread and a projecting lug, a centrally orificed closure disk for said outlet seated on said neck and peripherally notched to receive said lug, being thus restrained from rotation, an annular cap having a thread engaging the neck thread for detachably mounting said disk on said neck, and a shutter mounted on the disk for opening and closing the orifice of the closure.

2. In a dispensing mechanism for bulk material, a container for such material having a downwardly directed outlet, a closure for said outlet formed with a smaller outlet, a funnel-shaped member within the container for guiding discharging material to said orifice, an agitator carried within the container upon the funnel-shaped member, a shutter carried by and beneath said closure for opening and closing said smaller outlet, and means for rotating the funnel-shaped member responsive to travel of the shutter.

3. A dispensing mechanism for bulk material as set forth in claim 2, said funnel-shaped member having an outlet portion rotatable in said smaller outlet, and said means for rotating said member including a gear and elements fixing such gear on said outlet portion and extended into said portion to exercise an agitating effect.

WILLIAM J. KILPATRICK.
